Fig. 1

FIG. 2

FIG. 3

FIG. 4

FIG. 5

*FIG. 6*FIG. 1 is a front elevational view of a portable utility cabinet for service stations or the like showing our new design;

FIG. 2 is an elevational view taken from one side thereof, the opposite side being a mirror image of the side shown;

FIG. 3 is a rear elevational view thereof;

FIG. 4 is a top plan view thereof;

FIG. 5 is a bottom plan view thereof; and

FIG. 6 is a perspective view of a modification of a portable utility cabinet for service stations or the like shown in FIGS. 1 to 5, inclusive, differing therefrom in that the top of both the front and rear in said modified form are the same as the rear of the form shown in FIGS. 1 to 5.

We claim:

The ornamental design for a portable utility cabinet for service stations or the like, shown and described.
